Application September 3, 1946, Serial No. 694,644

5 Claims. (Cl. 310—93)

1

This invention relates to a control system and more specifically to a system for controlling the operation of a motor driven press welder. In the operation of that class of heavy machinery such as punch presses and press welders which perform a pressing, stamping or clamping operation a heavy ram is provided which is moved with respect to a stationary platen. Conventional driving means for the ram in these machines has heretofore been in the form of a large heavy flywheel that is driven by the motor and suddenly clutched to the driving means for the ram by means of a jaw clutch. This causes high initial stresses in the parts and attendant noise and vibration. It also makes the service problem a major one. In order to eliminate the problems attendant such construction and provide a smooth rapid acceleration of the ram it is proposed to utilize an electromagnetic clutch between the flywheel and the ram drive so that there will be no direct mechanical connection between parts which will be driven by a magnetic flux interlinkage.

It is therefore an object of our invention to provide a control system for an electromagnetic drive for heavy machines.

It is a further object of our invention to provide a control system for an electromagnetic clutch and brake for heavy machines.

It is a still further object of our invention to provide a control system for an electromagnetic drive for press welding machines.

With these and other objects in view which will become apparent as the specification proceeds, our invention will be best understood by reference to the following specification and claims and the illustrations in the accompanying drawings, in which:

Figures 1 and 1A form parts of a complete circuit diagram of the control system of my invention and Figure 2 is a diagrammatic showing of cam switch operation associated therewith.

Figure 1 and Figure 1A are combined by connecting the four lines at the bottom of Figure 1 as indicated by arrows with similar four lines at the top of Figure 1A.

Figure 2 is a diagrammatic showing of the phased mechanical operation of the cam operated switches.

Figure 3 is a schematic diagram of the drive between the motor and movable machine part.

Inasmuch as each relay coil when energized actuates a plurality of switch contacts either to open or close the same, it would be confusing to show on the drawings the connections between

each relay actuating coil and its associated contacts and so for purposes of this application the relay coils will be designated by letters, such for example as "A" and the contacts actuated thereby by the same letters plus identifying numerals such as A1 and A2 etc., depending upon the number of contacts actuated thereby.

Referring now more specifically to the circuit, there is shown a three phase power supply, lines 10, 12 and 14 connected to a main control switch 8, three input conductors, lines 10, 12 and 14 being connected to the opposite side of the switch. Line 10 terminates in a pair of parallel conductors 16 and 18 which are in turn connected to one terminal 20 of the three phase driving motor 22. In each of the lines 16 and 18 there is a switch F1 and R1 respectively. Lines 12 and 14 are cross-connected by lines 24 and 26, which connections have serially incorporated therein switches F2 and F3 respectively. Serially interposed in lines 12 and 14 are switches R2 and R3, line 12 being connected to terminal 28 and line 14 to terminal 30 of motor 22. Connected across lines 12 and 14 by lines 36 and 38 is primary 32 of transformer 34. This is a power transformer which provides the necessary energy for the various actuating relays. Lines 36 and 38 are connected ahead of the various switches F2, F3, R2, R3 so that the transformer will be energized as soon as the main switch 8 is closed. Power line 40 is connected to line 12 between these switches and the motor 22 and the associated power line 42 is connected to line 14 in like manner. These latter lines therefore are not energized unless either the series F switches or the series R switches are energized. It will thus be obvious that as soon as the main power switch is closed the motor will be energized to run in one direction by the closure of the F series switches, or forward, or it may be energized to rotate in the opposite direction or reverse by the closure of the R series switches.

Secondary 44 of transformer 34 has line 46 connected to one terminal and 48 connected to the opposite to provide lower voltage power leads than lines 40—42, to provide current for the various relays and further switches. Directly connected across between these lines is an indicator lamp 50 which indicates to the operator whether or not the power supply is energized. Directly connected in series relation between lines 46 and 48 are a series of control switches and energizing coils for controlling the forward and reverse contacts F and R which include a switch 52, a stop switch 54, a manually closed switch

56 which the operator closes to energize the motor 22 in a forward direction, a normally closed contact R4, relay coil F and a normally closed contact 58 which is thermally controlled by motor temperature and is operated by coils 60 in the motor line. Thus if the temperature of the motor exceeds a certain value this safety switch 58 will open. It will thus be obvious that switches 52, 54, R4 and 58 under normal conditions would be closed and therefore when the operator depresses switch 56, relay coil F will be energized to close the F series contacts and energize the motor 22 to rotate in a forward direction. In shunt around the switch 56 is a normally open contact F4 which is closed upon the energization of the F coil to maintain coil F energized but permit release of switch 56.

In parallel to that portion of the circuit just described including switch 56, contact R4 and relay coil F is a second circuit for controlling the reverse rotation coil R which has in series with it a contact F5 which is closed when relay coil F is de-energized, a reverse switch 61 operated by the operator and a similar hold in shunt switch R5 which by-passes manual switch 61. Through this circuit relay R can be energized by the manual closure of switch 61 which in turn actuates all the R contacts and causes the motor to run in a reverse direction. At this point it will be obvious that there is provided conventional switching means for a three-phase motor to cause the same to rotate in either one of two desired directions.

This motor is mechanically connected to a flywheel which must be placed in spaced driving relation with some means on the shaft of the press so that the same will operate. This is accomplished through magnetic flux clutching means between a drum on the press shaft and this flywheel.

The control for the magnetic clutching means will now be described. Switch 62 is directly connected to line 46 for power and is operated or maintained in normally closed position by air pressure in a line (not shown) which provides air to booster cylinders to give the press an initial push to start the same. Thus, under normal conditions this switch would be closed as long as air pressure is provided to the cylinders. A second switch 64 is connected in series with the switch 62 and also is normally closed by air pressure, but in this instance it is by the air pressure provided to the solenoid operated air brake so that the device will not operate unless air is being provided to the brake system. Further in the series connection with the two switches 62 and 64 is a fuse 66. A series of emergency stop buttons 68, 70, 72 and 74 next follow in series relation but placed, of course, in various convenient places around the machine and are normally closed but can be opened to deenergize the whole system if the necessity arises.

Connected to the last of the emergency switch buttons is a relay contact H1 which is opened upon deenergization and is controlled by the relay coil H which is itself connected across power lines 46 and 48 and has in series therewith only the "inch-run" switch 76. It will be obvious that when this switch is moved to the position shown or "run" position the relay coil H will be energized, but when it is moved to its upper contact 78 relay coil H will be deenergized and the machine will be capable of inching operation only which will be described. In

continued series relation there is connected contact R6 which is closed when the relay coil R is deenergized and opened upon energization of relay coil R, therefore when the motor 22 is running in reverse direction this circuit may not be energized. Line 80 is connected at a point between switch 74 and contact H1 and extends to contactor C1 which is in turn serially connected with contactor S1 and relay coil E, the opposite terminal of which is connected to power line 48. Coil E is the relay control coil for the solenoid operated mechanical brake.

Line 82 is connected at a point between contactors H1 and R6 and extends to normally closed contactor LS8 which is operated by one of a series of synchronously driven mechanical cams which appear in Fig. 2 and whose relationship is adjustable and will be later described in more detail. Contactor LS8 is in turn serially connected with contactor LS3 and contactor E3 which is opened upon deenergization of coil E and closed upon energization thereof. Connected to line 80 is a normally closed contactor H2 which is opened whenever relay H is energized, which under all normal conditions is when the switch 76 is in run position. In series with contactor H2 is a manually operated switch 84 which is the inch operation switch. In other words, when switch 76 is moved to contact point 78, the operator may then inch the machine along by closing switch 84 and opening it when the machine has proceeded to the desired point. Continuing in serial relation to switches H2 and 84 is switch L1 which is controlled by the relay coil L which in turn is directly connected across the power lines 46 and 48 and has in series therewith only a time delay operated switch 86. This is controlled by an electronic thermal relay 83 in circuit with the power tubes 90 and 92 which provide current for the magnetic brake and clutch and this prevents the operation of the whole circuit until the tubes have had an opportunity to heat up.

Continuing in the series relation with the main control line are a series of what is known as run buttons or manually operated switches 94, the number depending upon the number of operators which the machine is to have, two buttons being provided per operator. These switches are normally biased to upper position as shown and when in that position close the circuit through relay coil A to power line 48. When, however, they are in depressed position they tend to complete a circuit through relay coil B. In series relation, however, to the circuit for relay coil B there is a second contactor L2 operated by coil L which maintains the switch L2 closed during the running period of the machine. Also in series relation to coil B is a contactor A1 which is controlled by relay coil A and is closed when this coil is energized. To the left of the series of switches operated by the run buttons in this circuit is a switch contactor M1 which is closed upon deenergization but opens upon energization of the relay coil M which is the weld cycle initiating relay the intent being to maintain this circuit open when the welding control is dominating and actually performing welds so that the press motor may not be moved at this time.

A conductive line 96 is connected between switches R6 and 94 and extends to a cam operated switch LS2, the opposite side of which is connected to line 98, which in turn extends to

an intermediate point between switches B1 and B2. In shunt relation around the cam operated switch LS2 is a second cam operated switch LS7. Also connected to line 96 is a contactor N1 which is controlled by relay coil N and closes upon energization thereof. In series with this switch is a pressure actuated switch 100 which is maintained closed by pressure in the welding gun return line and opens upon the release thereof. The opposite side of the pressure switch is connected through line 102 with a point intermediate switches A1 and L2. The two lines just to the left of coils C and D which are shown by arrows are connected into the selector switch on the weld timer. The inch and run switch 76 is shunted by contactor M2.

Coils J and K which are connected in parallel are the coils primarily intended to actuate the dynamic brake of the drive and have serially in sequence the following switch contactors: H3, 20 LS4, P1, the latter contact being opened when the press is not in motion and closed when it is in motion, and L3. Shunting contactor LS4 is a second cam actuated contact LS9 and shunting both contactors H3 and LS4 is a contactor D1. A holding circuit for relay coil A is provided around the run buttons 94 through conductive line 104 which has in series relation three contactors LS1, LS3 and A2. The mechanical solenoid brake is set under normal spring bias and the relay E is energized to remove the braking pressure by closure of two contacts E1 and E2 which are in series with the brake coil T. The three elements being in series across the lines 46 and 48.

The relay coil M is the welding cycle initiating relay and when this coil is energized the welding machine proceeds through its normal cycle of welding, the press during this time remaining in stationary clamped position. Serially connected with the relay coil M are the following switch contactors LS5, H5, E4, P2, open when press is not in motion and closed when press is in motion and N2. Connected at an intermediate point between switches H5 and E4 in this series connection is a line 106 which extends to a control circuit from the welder indicated by the two downwardly directed arrow tipped lines shunted by a switch 108 and thence to the relay coil N. This switch 108 is a limiting switch which is operated by the last contact of the welder timer. In shunt around this welder controlled switch is a holding contactor N3. In series with the relay coil P between lines 46 and 48 is a controlling switch 110 which is operated by the speed of the member driving the platen and is closed at low speeds and opened at higher ones, such for example as those above 40 R. P. M.

The power transformer 112 which supplies the power for the magnetic clutch and brake has its primary 114 connected across lines 40 and 42 of the power supply and has in series therewith two control contactors D2 and C2 and in shunt relation around each of these contactors are further switch contactors K1 and J1 respectively. The secondary 116 of this transformer is center tapped and connected to line 118. One of the outside terminals is connected through line 129 with a rectifier tube 99 the opposite secondary terminal is connected through line 122 to a second rectifier tube 92. Supplying the filament power for these rectifier tubes is a transformer 124 whose primary 126 is connected between lines 40 and 42 and whose secondary 128 has its two outside terminals connected to lines 130 and 132 75

which extend to the filament circuits of tubes 90, 92 and 88. Secondary 128 is also center tapped and line 134 connected thereto.

The operating coil 136 for the electromagnetic clutch is connected directly between lines 134 and 118 and has in series relation thereto coil S which is provided with some time delay means, switch contactor D3 and C3, on one side and a pair of torque limiting resistors 138 and switch contactors C4 and D4 on the opposite side. The two torque limiting resistors 138 are by-passed by a shunt circuit which includes switch contactors H5 and H4. The dynamic brake coil on the other hand shown at 140 is also connected between lines 134 and 118 and has in series relation therewith on one side contactor J2 and K2 and on the opposite side K3 and J3.

Figure 2 diagrammatically shows the phased mechanical operation of the various cam operated switches, the shaded portions indicating the time periods in a complete cycle of rotation during which the switch actuated thereby is closed and the unshaded or clear portions that period of time during which that switch is open, a full cycle of the ram being thus represented by a flat rectangle and showing that time during which the machine starts from its initial lowered position, is raised to clamp the welding electrodes which are then fired and the platen lastly returned to its lowermost position. The diagrams as will be noted are numbered from 1 to 9 and the switches in the circuit diagrams of Figs. 1 and 1A have been identified as LS1, 2 or 3 as operated by cams 1, 2 or 3 of Fig. 2.

35 In Figure 3, the motor 22 is shown provided with a pulley 23 driving a rotatable flywheel 25 through a belt 27. The flux generating coil 136 is carried by the flywheel. Rotatably mounted within the flywheel is a spider 29 made of magnetizable material which is an integral part of a shaft section 29'. A crank 31 is rigidly connected to the outer end of the shaft section and a link 33 is pivotally connected to the crank end and to a movable part 35 of a machine or press which it is desired to drive or move. A friction brake 37 is spring biased to engage the shaft to prevent its rotation by spring 39 and may be moved away from braking position by solenoid E. The flux brake coil 140 is supported on a stationary drum 41 within the spider. Thus, with the flywheel continuously rotating when coil 136 is energized, the spider will be driven thereby through the flux linkage and when the coil 136 is de-energized and coil 140 energized the spider will have a braking action applied due to the stationary flux field. The friction brake is operated to remove the braking action by energization of coil E in proper timed relation as will be further described.

60 The operation of the device will now be explained in detail. Assuming that the machine is de-energized and in a position of rest, which under normal circumstances would be when the platen is in lowered position ready for the insertion of a part to be welded between the upper and lower electrodes, the switches all being shown, either open or closed in the position when its operating coil is de-energized. Switch 8 is then closed which applies power to transformer 34. The power circuit to the driving motor 22 may be completed by closing of either switch 56 or 61 as the case may be depending upon whether the operator desires the motor to run in one direction or the other.

Let us assume that it is desired to energize the motor so that it will run in a forward direction, the operator then closes switch 58 which completes an obvious circuit through coil F since all of the remaining contactors in that circuit are normally closed by either safety switches or interlock switches. The energization of coil F therefore causes the F contacts in the power line to close and the motor 22 will rotate in the forward direction.

Transformer 112 and transformer 124 are now energized and until the tubes 99 and 92 have heated a predetermined length of time, none of the remainder of the control circuits may be energized. This is due to the fact that electronic thermal switch 88 will not permit the closure of time delay switch contacts 86.

Since, however, the motor is not clutched to the ram drive no movement of the latter will be affected. In order to move the ram up into welding position the clutch must be energized. After a sufficient time period has passed to cause the thermionic time delay means 88 to conduct, it closes switch 86 which in turn energizes relay coil L. Assuming further that it is desired to "run" rather than "inch" the press, switch 76 is moved to its lower position completing the circuit through relay coil H and that is therefore also energized.

This completes a circuit through relay coil A as follows: Power line 46, normally closed switches 62, 64, 68, 78, 72, 74, switch H1, switch R6 which is normally closed when relay coil R is de-energized, a series of switches 94, coil A to power line 48. As soon as this circuit is completed, a holding circuit for relay coil A is provided through line 104, switches LS1, LS6 and contactor A2 which is now closed. Referring momentarily to Fig. 2 it will be seen that cam controlled switches 1 and 6 are closed at this time since the shaded portion of these diagrams begins at the upper or zero position of rotation. Relay coil A being energized, A1 is now closed, switch L2 has previously been closed as soon as the time delay contacts are closed as previously described, and switch M1 is closed inasmuch as relay coil M is de-energized. As soon therefore as all the run buttons 94 are depressed by the operators, relay coil B will be energized through an obvious circuit which closes switches B1 and B2 thus completing a circuit through relay coils C and D. The reason for these two coils being connected in parallel and operated simultaneously is strictly for safety reasons. Thus, if contacts operated by one freeze in, the other will still operate the circuit normally since the contacts operated by the two are always in series and the device will not assume any abnormal operation.

The energization of these two coils C and D opens contactor D1 and closes contactors C1, C2, D2, C3, D3, C4, and D4 to complete the power circuit to the clutch coil 136 energizing the same. This magnetically locks the motor to the press drive and the ram begins to ascend since the mechanical brake is also released by the energization of C and E. If the clutch does not become energized, through a tube or brush failure, the series relay S does not pick up and consequently the S1 contact in series with relay E does not allow the spring set magnetic brake to release. However, if current flows through the S relay the magnetic brake will release simultaneously with the closing of the contacts D3 and C3, C4 and D4 and the press will operate

through approximately 155° of rotation on the depression of buttons 94, at which time cam number 2 operating the LS2 switches will close which by-passes the run buttons 94 which may then be released and the cam LS2 controls the rotation, as shown by the shaded portion in the middle of cam 2 on Fig. 2.

During the time the cam 2 takes over cam 1 allows its contacts LS1 to open de-energizing relay coil A which provides an anti-repeat operation should the run buttons still be depressed. This permits cam LS2 to control the energization period of coils C and D and release them at a predetermined point slightly less than a 180°. When these coils are de-energized the magnetic clutch, of course, immediately ceases to drive. Just as the clutch is released the dynamic brake is energized by the closing of the LS4 contacts in series with the coils J and K, and acts to bring the moving member to rest. As the ram comes to rest LS3 opens to set the magnetic brake and hold it. Therefore the dynamic brake stops the load and the mechanical brake holds it.

As previously described, the coil H is energized so that switch H3 will be closed and also coil L has been energized closing contacts LS3. Therefore, when cam 4 reaches a predetermined point, LS4 will close energizing coils J and K which, referring now to the bottom of Fig. 1A, completes an obvious circuit through the dynamic brake coil 140. This combined braking action will bring the press to a stop between dead center and 10° ahead of this point and is controlled by the setting of the cam 4. As soon as motion has ceased relay P opens due to the zero speed switch 118 to de-energize the dynamic brake, the mechanical brake holding the device stationary.

In order to insure that the welding is actuated at the proper time it is controlled by the cam switch 5 which is closed only within the desired range. Therefore, the weld initiating relay M is controlled by contact LS5, the zero speed switch relay P and the magnetic brake relay E which, of course, control the operation of switches E4 and P2 in the series circuit, switch H5 being closed as previously described and N2 being normally closed upon coil de-energization as well as E4. The energization of coil M sets the normal welding cycle off and the welding guns are fired. To assure that welding pressure will be maintained on the work throughout the welding cycle, the shunt circuit around switch 76 is closed by contactor M2 so that even if switch 76 is accidentally opened the circuit will still be maintained. After the last gun is fired a contact in the timer, switch 108, energizes relay N which immediately closes contactor N3 and completes an obvious holding circuit around switch 108 to hold in relay N. This also causes switch N2 to open, de-energizing relay coil M, which completes the welding cycle. The energization of relay N also closes switch N1 which by-passes the run buttons and starts the press on the down stroke or last half of the cycle. This completes a circuit for the energization of coil B through line 96, switch N1, switch 109, line 102, switch L2, relay coil B and this re-energization of coil B closes contactors B1 and B2 to again energize the magnetic clutch coils C and D and in turn the magnetic brake relay E to release that brake.

As previously described, this action clutches the drive motor 22 to the driving means for the press releases the brake and the press begins to

descend. After rotation of a few degrees beyond the welding position, cam 7 assumes control by the closure of cam operated switch LS7 to maintain energization of coils C and D, by-passing contactor N1 which initiated the movement. The press continues automatically to move downward until the clutch is de-energized by the opening of switch LS7 slightly ahead of its completion of 360°. As the clutch releases the dynamic brake is energized by control of contact D1 or cam 9 in its operation through switch LS9 which by-passes or is in parallel with switch LS4 in the circuit to coils J and K. This dynamic brake remains on until approximately the end of the cycle and the magnetic friction brake sets slightly prior thereto through action of cam operated switch LS8. When the press stops, the dynamic brake is released by the zero speed switch 110 which de-energizes coil P dropping out coils J and K and their associated contacts.

It might be mentioned at this point that there is a second anti-repeat cam LS6 in series with the first cam LS1 to prevent re-energization of coil A and thus the continuation of the press past the 360° cycle. If any of the buttons 94 are released during approximately the first 155° of travel, the press will stop by action of the dynamic and mechanical brakes, but if 155° is past, cam LS2 takes over and the press will go through its operation. This operation of pressing the buttons of course, is repeated each time it is desired to operate the press welder.

Assuming now that it is desired to inch the press rather than to drive the same through a full cycle, switch 76 is placed on contact 78 for operating position. The press rotation is then directly under the entire control of the manually operated inch button 84 and whenever it is depressed an obvious circuit through relay coils C and D will be completed to energize the clutch coil 136 and the press will be driven. However, in this case coil H is not energized and the by-pass around limiting resistors 130 remains open and the resistors are placed in series with the magnetic clutch 136 to cut down the current flow therethrough to a smaller amount to reduce the flux so that the driving force will be less. Whenever the inch button is released the brakes will be immediately set. The welding sequence during inching operation will not function since the relay M cannot be energized due to the fact that the contactor H5 remains open. The welding guns however can be actuated manually by the closing of a selector switch on the weld timer which by-passes a switch operated by the coil M (not shown).

If it is desired to operate the motor in the reverse direction the switch 61 instead of switch 56 is depressed and the motor will be rotated in that direction. As soon as switch 61 is pressed to energize coil R, hold in switch R5 will be closed to maintain the motor operating in this direction. This action also causes switch R6 to open, since this is a switch which is normally closed. This opens the circuit for the run buttons 94 and makes them inoperative. The magnetic clutch and solenoid brake can now only be actuated by the "inch" switch 84, the clutch being energized and the brake released when switch 84 is closed and vice versa when the same is released, since it controls the energization of coils C and D.

We claim:

1. In a control system for a press, a source of power, a motor connectable to said source, rotatable means for driving said press, magnetic

flux clutch means between the motor and the rotatable driving means, energizing coils mounted in the clutch means, dynamic flux brake means associated with the rotatable means to stop the same, a second series of energizing coils for the brake means, a solenoid released friction brake applicable to the rotatable means, switching means for controlling the clutch and brakes to simultaneously energize the flux clutch and release the friction brake and at a different time to deenergize the flux clutch and energize the brakes to stop the rotatable means including alternate control means to provide continuous drive for the press through an operating cycle or to move at small distances as desired, and additional switching means in a shunt circuit to the alternate control means to maintain a continuous circuit through a given portion of the cycle once it has been started.

2. In a control system for a press, a source of power, a motor connectable to said source, rotatable means for driving said press, magnetic flux clutch means between the motor and the rotatable driving means, energizing coils mounted in the clutch means, dynamic flux brake means associated with the rotatable means to stop the same, a second series of energizing coils for the brake means, a solenoid released friction brake applicable to the rotatable means, switching means for controlling the clutch and brakes to simultaneously energize the flux clutch and release the friction brake and at a different time to deenergize the flux clutch and energize the brakes to stop the rotatable means, a master switch controlling the first-named switching means for continuous operation for a cycle of the press, a shunt circuit around the master switch, and additional switching means in the shunt circuit to close the same during a portion of the cyclic operation to assure continued operation of the press even though the master switch may be opened.

3. In a control system for a cyclically operating press machine, a source of power, driving means connectable to said source, operating means for the press, magnetic flux clutch means between the driving means and the operating means, dynamic flux braking means applicable to the operating means, mechanical solenoid brake means applicable to the operating means, switching means for controlling the clutch and brakes to initially energize the flux clutch and remove the magnetic brake at the beginning of a cycle in moving from a position of rest, energize the flux brake, deenergize the flux clutch and apply the friction brake when the press is in clamping position at an intermediate portion of the cycle, further switching means actuated at the termination of the clamping portion of the cycle to again cause actuation of the first-named switching means to energize the flux clutch and remove the friction brake to return the apparatus to a position of rest, and a holding circuit for the further switching means to assure return to the rest position.

4. In a control system for a press, a source of power, a motor connectable to said source, rotatable means for driving said press, magnetic flux clutch means between the motor and the rotatable driving means, energizing coils mounted in the clutch means, dynamic flux braking means and mechanical solenoid braking means applicable to the operating means, energizing coils in the flux braking means, combination relay and cam controlled switching means to en-

ergize the flux clutch coils and remove the friction brake to cause the press to move from a position of rest to a position slightly in advance of the clamping position and then deenergize the flux clutch, energize the flux brake and then apply the friction brake to stop the press in clamping position to perform work on a clamped part, additional switching means actuated by the completion of the acts performed upon the clamped part to cause the clutch and brake control switching means to recycle to bring the press back to a position of rest, and locking means for the additional switching means to assure return to the rest position.

5. In a control system for a press having a platen that moves from a position of rest to full clamping position to clamp work members upon which acts are to be performed and then returned to rest position, a source of power, a motor connectable to said source, rotatable means for driving the platen, magnetic flux clutch means connected between the motor and the rotatable driving means to couple the same, magnetic flux brake means applicable to the rotatable means and solenoid friction brake means applicable to the driving means, switching means connected between the source of power and the magnetic flux clutch and brake and solenoid brake to energize and deenergize same in time relation to move the platen to clamping position, hold it there for a predetermined time until acts have been performed on the work members

10

25

30

and then move said platen back to a position of rest, said initiation of the movement back to rest position provided by the completion of the acts performed upon the work and locking means to maintain operation until the platen has returned to rest.
